B. L. AMES

SOOT BLOWER TUBE MOUNTING

Filed August 19, 1921

FIG. 1.

FIG. 3

INVENTOR:
Bradford L. Ames,
BY Maxfield, Baldwin & Copeland, Attys.

UNITED STATES PATENT OFFICE.

BRADFORD L. AMES, OF BOSTON, MASSACHUSETTS.

SOOT-BLOWER-TUBE MOUNTING.

Application filed August 19, 1921. Serial No. 493,568.

One object of the invention is to provide a rotor connection between a nozzle and a steam supply pipe in such manner that if the steam supply pipe is set in a vertical position the nozzle will be in a plane at an acute angle to the horizontal and always be maintained at the same angle of pitch throughout all the sweeping movement of the nozzle.

10 The invention is especially intended to be applied to use with soot blowers for water tube boilers in which a plurality of nozzles are employed to inject steam to clean the tubes. It is further especially intended for 15 application to that class of water tube boilers in which the boiler tubes are set in a plane at a slight pitch to the horizontal. One object of the invention is to provide such a construction of the pipe fitting and 20 rotor and nozzle connections that the nozzles will always be maintained at the same angle of pitch as the plane of the boiler tubes throughout the entire sweeping movement of the nozzles.

25 The invention will be fully understood from the following description when taken in connection with the accompanying drawings, and the novel features thereof will be pointed out and clearly defined in the 30 claims at the close of this specification.

In the drawings, Fig. 1 is a view in elevation showing a portion of a water tube boiler furnace having apparatus embodying the invention.

35 Fig. 2 is an enlarged sectional view showing the rotor connection of one of the nozzles with one of the fittings.

Fig. 3 is a section on line 3—3 of Fig. 2.

Referring now to the drawings, 1 represents the brick setting of a boiler furnace, 2 the steel casing and mount for the soot blower apparatus, 3 a series of tubes which 40 form a part of the boiler, and 4 a vertical steam feed pipe for supplying steam to the 45 series of nozzles 5.

The boiler tubes 3 are set at a slight angle of pitch one above another, it being understood that as usual there are a number of series of boiler tubes in different planes of 50 elevation, those in each series being at the same elevation. Only one tube of each series is shown in the drawings.

Each nozzle 5 has a swivel connection with a port 26 in the side of a branch member 6 which is mounted in an opening 7 in the side of the vertical steam feed pipe 4,

so that each of said nozzles may be allowed to swing and to direct its discharge of steam in a wide sweep between the boiler tubes. Each nozzle extends between the planes of an upper and a lower series of boiler tubes. It is important that the nozzle should be parallel with the boiler tubes in all the various ranges of sweep. I provide a peculiar construction of swivel connection between the nozzles and the branch member 6 so as to maintain each nozzle at the same angle of inclination to the plane of the boiler tubes throughout all its various movements as it turns on its axis of oscillation.

70 The feed pipe 4, as already stated, preferably stands in a vertical position. The branch members 6 are fixedly secured to the feed pipe 4, preferably by being screwed therein, and each having a port 7 which 75 leads from the steam supply pipe to the branch 6. The branch member 6 extends at right angles to the feed pipe 4 and therefore its axis is horizontal.

Each nozzle 5 preferably is located at a 80 slightly higher elevation than the member 6 so that its connection with the member 6 is on the upper side thereof. Each member 6 is connected with an elbow 8 which has a downwardly extending arm 8^a whose axis 85 is at right angles to the longitudinal axis of the nozzles 5 so that as the nozzle 5 is at a slight angle of pitch to the horizontal, the axis of the arm 8^a of the elbow will have 90 an angle of pitch with relation to the vertical equal to the same angle of pitch of the nozzle 5 to the horizontal. For instance, if the nozzle 5 is pitched at an angle of 5° to the horizontal, the axis of the elbow arm 8^a will be at an angle of 5° to the vertical. 95 Correspondingly, as the axis of the member 6 is horizontal the axis of the elbow arm 8^a will be inclined at an angle of 85° to the longitudinal axis of the member 6.

In the case assumed, the boiler tubes 3 100 are also supposed to be at an angle of pitch of 5° to the horizontal, and each nozzle 5 should in its oscillating movement swing in a plane which is always at an angle of 5° to the horizontal.

105 The swivel connection of the nozzles with the member 6 is by means of a rotor 10 which is screwed into the arm 8^a of the elbow 8 and has a swivel connection with an annular cap or curb 11 connected to the member 6. Said curb 11 is provided with 110 a flange 12 which rests upon a flat seat 13

on the upper side of the member 6 and is secured thereto by screw bolts 14.

Said curb 11 has an upwardly extending shank formed with an annular flange 15 whose axis is pitched at the same angle as the axis of the arm 8^a, and has an under surface 16 which is in a plane pitched at an angle which is at right angles to the axis of the said shank of the curb and which is 10 parallel with the plane in which the nozzle 5 moves. The rotor 10 has a flange head 17, the upper face 18 of said flange being seated upon the annular surface 16 of the curb and being pitched at the same angle. The said 15 rotor has a smooth periphery at that portion which engages with the inner periphery 19 of the flange portion 15 of the curb so that it can readily turn therein.

Thus it will be seen that in all movements 20 of the nozzle it will swing in a plane which is at a uniform angle of pitch and which is at the same angle of pitch as the boiler tubes.

Any suitable means of rotating the said nozzles may be employed. The means shown 25 are the same as shown in a companion application by me, filed August 19, 1921, Serial No. 493,567. Briefly such means is as follows: Two vertical guide rods 20—20 are provided between which each nozzle extends. 30 Said guide rods are mounted in lugs 21 which are rigidly connected with and form part of a gear 22, said gear 22 meshing with a worm 23 formed on the shaft 24 which projects through the front wall of 35 the furnace. By rocking said shaft 24 by an operator in front of the furnace, said gear 22 will rock and thereby oscillate the guide rods 20, thereby oscillating and swinging the nozzles 5. Said guide rods also pass 40 loosely through two or more brackets or hangers 25 which have pivot connection with two of the members 6.

By this form of construction in which the member 6 is made in two sections as described, there is a great advantage both in assembling and being easily accessible for repairs. It can be readily seen that the members 6 being screwed in at right angles to the vertical supply pipe the parts are 45 more certain of being put in proper position in relation to each other than if the members 6 had to be located in a plane parallel to the pitch of the tubes. The flange seat for the rotor being machined at the same pitch as the tubes, makes it almost impossible to have the nozzles in any other than their proper position in relation to the pitch of the tubes.

Whenever it is desired to remove any one 50 of the nozzles and its rotor, whether it be

either one of the end nozzles and its rotor or one of the intermediate ones, access may be easily had by means of a suitable tool to unscrew the bolts 14 of the rotor that it is desired to remove, which secure the rotor 65 to the branch member 6, and then the rotor with the attached nozzle may be easily lifted out without disturbing any of the other parts. The member 6 is left unmoved.

What I claim is:—

1. In combination with a water-tube boiler, a steam supply pipe, a branch member communicating therewith having an outlet opening, a curbing surrounding said outlet having at its inner end an outwardly extending peripheral flange detachably secured to the outer face of said branch member, said curbing having at its outer end an inwardly extending flange provided with a facing parallel with the plane of the pitch of the boiler tubes, a tubular rotor having a swivel connection with said facing for turning on said facing, an elbow having one arm secured to the outer end of said rotor, and a nozzle tube secured to the end of the 80 other arm of said elbow, whereby when the said rotor rotates on its axis the nozzle tube will swing in a plane parallel with the planes of the boiler tubes, the combined nozzle tube, elbow, rotor and curbing being bodily removable as a unit by detaching the curbing from the said branch steam pipe.

2. A soot blower for water-tube boilers having a steam pipe formed with a flat face in its periphery having an outlet opening therethrough, a curbing surrounding said outlet detachably secured to said steam pipe, the axis of said curbing extending at an inclination to the said flat face of the steam pipe, said curbing having at its outer end an inwardly extending annular flange whose inner face is in a plane at a pitch to the flat face of the steam pipe, a tubular rotor whose axis of rotation is at a right angle to said flange and is inclined to the said flat 105 face of the steam pipe, and having at its inner end an annular flange whose outer face engages with the inclined inner face of the outer flange on said curbing, the outer periphery of the rotor above its flange engaging with the inner periphery of said outer flange of the curbing in such manner as to form a swivel connection between the rotor and the curbing, an elbow provided with means engaging the outer face of said annular flange 110 and having an arm secured to the outer end of said rotor, and a nozzle tube secured to the end of the other arm of said elbow.

In testimony whereof I affix my signature.
BRADFORD L. AMES,
